[57] **CLAIM**

The ornamental design for C. B. radio, substantially as shown and described.

DESCRIPTION

FIG. 1 is a perspective view of a C. B. radio showing my new design;

FIG. 2 is a top plan view thereof;

FIG. 3 is a front elevational view thereof;

FIG. 4 is a bottom plan view thereof;

FIG. 5 is a side elevational view thereof;
FIG. 6 is a side elevational view thereof opposite to that shown in FIG. 5.

The rear of the C. B. radio is substantially flat and unornamented.
